(57) **CLAIM**

The ornamental design for a vehicle fender, as shown and described.

DESCRIPTION

FIG. 1 is a front, first side, and top isometric view of a first embodiment of a vehicle fender embodying the new design; FIG. 2 is a front, second side, and bottom isometric view thereof;

FIG. 3 is a front view thereof;

FIG. 4 is a rear view thereof;

FIG. 5 is a second side view thereof;

FIG. 6 is a first side view thereof;

FIG. 7 is a top view thereof; and

FIG. 8 is a bottom view thereof.

FIG. 9 is a front, first side, and top isometric view of a second embodiment of a vehicle fender embodying the new design;

FIG. 10 is a front, second side, and bottom isometric view thereof;

FIG. 11 is a front view thereof;

FIG. 12 is a rear view thereof;

FIG. 13 is a second side view thereof;

FIG. 14 is a first side view thereof;

FIG. 15 is a top view thereof; and,

FIG. 16 is a bottom view thereof.

Broken lines are used to illustrate features and/or environmental structures and form no part of the claimed design.

1 Claim, 16 Drawing Sheets
